STRAND GUIDE

Alphonse F. Pieper, Brighton, N. Y.

Application February 16, 1954, Serial No. 410,647

6 Claims. (Cl. 242—157)

This invention relates to a strand guide of the general type used for winding yarn, thread, or other fibre materials from a supply spool or bobbin onto a cone or receiving package, and has for its purpose to afford a guide eye of practical and efficient light weight construction in which the strand-engaging surfaces are resistant to wear and abrasion so as not to be affected by continued usage.

A more particular purpose of the invention is to afford a guide eye consisting of a metal supporting body of minimum weight and provided with abrasion-resistant elements or surfaces at the points where the strand is in frictional engagement with the eye, thus protecting the refractory abrasion-resistant elements against breakage.

A further object of the invention is to afford a strand guide that can be economically produced and consists of a metal supporting body portion of novel and meritorious form and having abrasion-resistant surfaces or elements at opposite ends of the metal body arranged to receive and direct the strand of yarn or other material as it travels through the guide eye in engagement with opposite surfaces thereof at the ends.

Still an additional purpose is to afford in conjunction with a metal supporting body with loop-shaped ends, novel and improved forms of abrasion-resistant elements or surfaces and attaching them to the metal body in a manner that insures their rigid and permanent connection with the body.

To these and other ends, the invention consists in the construction and arrangement of parts that will appear clearly from the following description when read in conjunction with the accompanying drawings, the novel features being pointed out in the claims following the specification.

In the drawings:

Fig. 1 is a view in side elevation illustrating a preferred embodiment of the invention and showing the strand guide in the operative position it assumes in contact with a body of yarn being wound onto a cone;

Fig. 2 is a top plan view of the guide eye, with the base partially broken away;

Fig. 3 is a bottom plan view of the same;

Fig. 4 is a sectional view on line 4—4 of Fig. 2 looking in the direction indicated;

Fig. 5 is a sectional view on the line 5—5 of Fig. 4 looking in the direction indicated, and

Fig. 6 is a detail plan view of the metal supporting body of the guide eye.

Referring more particularly to the drawings in which like reference numerals refer to the same parts throughout the several views, the guide eye consists of a metal supporting body formed of a rod or stiff wire of approximately $\frac{3}{32}$ " in diameter or less and preferably of cylindrical cross-section, said wire being bent upon itself to afford two loop-shaped or curved ends 1 and 2, which are connected on one side by a straight continuous side portion 3 and on the other side by side portions 4 and 5 parallel

2

to and spaced from the first mentioned side portion 3. The side portion 5 terminates in an offset terminal portion 6 spaced from and parallel to the side portion 4, affording an opening 7 through which a strand can readily be inserted into the guide eye between the opposite parallel side portions.

The metal supporting body is preferably elongated approximately as shown, having a length considerably greater than its width in order to accommodate itself more readily and without interference with other parts of the winding mechanism as the wound cone increases in diameter, and the metal supporting body is mounted on a metal base or post 8 that may be of greater length than the eye and is readily attachable to and secured in a sleeve 9 formed at the upper end of a conventional supporting arm 11 mounted for pivotal movement toward and away from the cone or yarn body onto which the strand is wound as usual in this type of machinery.

The post 8 terminates at its upper end in a flat plate 12 that is secured in any suitable fashion as by soldering or otherwise to the under surface of the lower loop-shaped end 2 of the metal body, and 13 designates an abrasion-resistant element or tip that overlies the top surface of the loop-shaped end 2 of the metal body and the plate 12 on the under surface thereof. The abrasion-resistant element 13 includes a projection 14 of reduced diameter extending between the side portions of the loop-shaped end 2 of the metal body into engagement with the plate 12 and securely attached to the plate 12 and to the loop-shaped end of the body by soldering or in any other suitable fashion. The abrasion-resistant element or tip 13 is formed with a groove 15 through which the strand passes and against which it engages as it is fed to the cone on which it is to be wound, the abrasion-resistant element 13 being formed of any suitable material for the purpose and preferably fire-hardened in accord with established practices in the manufacture of such abrasion-resistant material. The abrasion-resistant element 13 entirely covers the upper surface of the lower loop-shaped end 2 of the metal body, so that as the strand of yarn indicated at 16 travels upwardly, it passes over the curved surface of the abrasion-resistant tip which defines the groove 15 and thence through the space afforded between opposite side portions of the metal body to where it passes under the upper end of the guide eye, as indicated in Fig. 1.

The metal body is protected at its upper end by a laterally curved abrasion-resistant element or tip 17 which is provided with a hollow interior of laterally curved formation so that it fits closely around and over the upper curved loop-shaped end 1 of the metal body and is attached thereto by suitable solder 18. The abrasion-resistant element or tip 17 is provided with a groove 19 having a curved bottom, and as the strand 16 passes from the lower abrasion-resistant element 13 through the guide eye, it travels thence through the groove 19 of the upper abrasion-resistant element under the latter and onto the cone. In this fashion, the strand is wound onto the cone without contacting any portion of the metal supporting body of the guide eye, all friction and wear being taken by the abrasion-resistant elements 13 and 17, and the structure can be used indefinitely since all wear is absorbed by the abrasion-resistant surfaces which are of such material that they are not affected by the friction of the strand passing in engagement therewith.

By producing the supporting body of the guide eye of light weight metal stock and protecting the ends of the metal body with abrasion-resistant material, it is possible to make the guide eye of minimum weight and of elongated form or any desired length and thus adapt it to a more efficient operation and so as to coordinate more successfully with large diameters of cones than guide eyes as heretofore constructed. The structure en-

3

ables producing a guide eye that is stronger, of considerably less weight, of lower manufacturing cost, and having abrasion-resistant surfaces that are protected and less likely to be broken, than devices heretofore available for the purpose, while the guide eye of elongated form avoids interference with other parts of the winding mechanism as the diameter of the cone increases.

While the invention has been described with reference to the particular structure shown, it is not restricted to the details herein disclosed, and this application is intended to cover such modifications or departures as may come within the purposes of the improvement or the scope of the following claims.

I claim:

1. A strand guide comprising a metal body in the form of an eye consisting of upper and lower loop-shaped ends connected by an elongated portion on one side and spaced side portions on the other side affording an opening therebetween which permits inserting a strand through the eye, and abrasion-resistant elements attached to and overlying outer surfaces of said upper and lower ends of the metal body and provided with strand-engaging grooves on the bottom and top respectively of said abrasion-resistant elements.

2. A strand guide comprising a metal body in the form of an eye consisting of upper and lower loop-shaped ends connected by an elongated portion on one side and spaced side portions on the other side affording an opening therebetween which permits inserting a strand through the eye, and abrasion-resistant element attached to and overlying the upper surface of said lower end of the metal body and having a strand-receiving groove in its upper surface, and an abrasion-resistant element surrounding and attached to outer surfaces of said upper end of the metal body and having a strand-receiving groove in its bottom surface.

3. A strand guide comprising a metal body in the form of an eye consisting of upper and lower loop-shaped ends connected at one side by an elongated continuous straight portion and at the other side by side portions spaced from and parallel to the first mentioned side portion, one of the last mentioned side portions terminating in an offset terminal portion parallel to and spaced from the adjacent side portion affording an opening through which a strand can be inserted, and abrasion-resistant elements secured to and overlying outer surfaces of said loop-shaped ends of the metal body and having grooves on the top and bottom respectively of said abrasion-resistant elements serving to receive a strand passing through the eye and onto a winding body.

4. A strand guide comprising a metal body in the form of an eye consisting of upper and lower loop-shaped ends connected at one side by a continuous straight portion and at the other side by side portions spaced from and parallel to the first mentioned side portion, one of the last mentioned side portions terminating in an offset terminal portion parallel to and spaced from the adjacent side portion affording an opening through which a strand

4

can be inserted, a base terminating in a portion attached to the lower loop-shaped end, an abrasion-resistant element overlying the upper surface of said lower loop-shaped end of the metal body and attached thereto, said abrasion-resistant element having a strand-receiving groove in its upper surface, and a second abrasion-resistant element surrounding the upper loop-shaped end of the metal body, said last mentioned abrasion-resistant element overlying the upper and lower surfaces of said end portion and attached thereto, and said last mentioned abrasion-resistant element having a groove in its lower surface to receive a strand passing through the eye and onto a winding body.

5. A strand guide comprising a metal body in the form of an eye consisting of upper and lower loop-shaped ends connected by an elongated portion on one side and spaced side portions on the other side affording an opening which permits inserting a strand through the eye, an abrasion-resistant element overlying the upper surface of said lower end of the metal body and attached thereto and having a projecting portion extending between said side portions of the lower loop-shaped end and attached thereto, said abrasion-resistant element overlying an outer surface of said loop-shaped end and having a strand-receiving groove therein, and an abrasion-resistant element attached to and overlying outer surfaces of said upper loop-shaped end of the metal body and having a strand-receiving groove in its bottom surface.

6. A strand guide comprising a metal body in the form of an eye consisting of upper and lower loop-shaped ends connected at one side by a continuous straight portion and at the other side by side portions spaced from and parallel to the first mentioned side portion, one of the last mentioned side portions terminating in an offset terminal portion parallel to and spaced from the adjacent side portion affording an opening through which a strand can be inserted, a base terminating in a portion attached to the lower loop-shaped end, an abrasion-resistant element overlying the upper surface of said lower loop-shaped end of the metal body and attached thereto, said abrasion-resistant element having a projecting portion extending between said side portions of the lower loop-shaped end and attached thereto, said abrasion-resistant element having a strand-receiving groove in its upper surface, and a second abrasion-resistant element surrounding the upper loop-shaped end of the metal body, said last mentioned abrasion-resistant element overlying the upper and lower surfaces of said end portion and attached thereto, and said last mentioned abrasion-resistant element having a groove in its lower surface to receive a strand passing through the eye and onto a winding body.
